ANTITORPEDO SHIELD

Wadsworth W. Mount, Summit, N. J.

Application November 19, 1942, Serial No. 466,111

13 Claims. (Cl. 114—240)

This invention relates to certain new and useful improvements in anti-torpedo shields.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Objects of the invention are to provide an improved anti-torpedo shield which may be towed by a vessel to which it is designed to afford protection throughout the length and depth of the vessel; which will follow a course substantially paralleling that of the vessel at all times; which will automatically change course in response to a change in course of the vessel so as to maintain the same parallel course relationship at all times; which will automatically correct its course to that of the vessel if deflected therefrom; which is adapted to be towed by a system of spring-line cables in spaced relation to the towing vessel and at any desired practical distance therefrom set by the length and weight of the cables so as to be substantially unaffected by wave action and by pitching and rolling of the ship and so that sudden shocks such as are caused by pitching and tossing of the ship will be absorbed by the cables rather than taken up by the ship or the shield; which is of sufficient strength to explode, deflect, stop or foul a torpedo before that same torpedo can strike the towing vessel; which is of sufficient size to protect the vessel throughout its length and depth without danger of fouling the vessels' propellers by the towing cables; which may be quickly cast off by the towing vessel without becoming a menace to navigation after it has served its purpose of protecting the vessel against the surprise element in a torpedo attack; and, which offers relatively little resistance to towing.

Of the drawings:

Fig. 1 is a semi-diagrammatic view in plan of a typical and illustrative embodiment of this invention, as applied to the safeguarding of a marine vessel;

Fig. 2 is a semi-diagrammatic view in front

elevation of the embodiment of Fig. 1 showing the relative depths of vessel and anti-torpedo shields;

Fig. 3 is a fragmentary view in side elevation of an anti-torpedo shield such as is depicted in Fig. 1, parts of the shield structure being broken away so as to show details of its laminated construction;

Fig. 4 is a fragmentary view in plan of the shield depicted in Fig. 3, showing details of the towing and steering devices;

Fig. 5 is a view in section taken along the line 5—5 of Fig. 3 showing details of the construction of the shield;

Fig. 6 is a fragmentary and somewhat enlarged view of a constructional detail of the shield of Fig. 5;

Fig. 7 is a fragmentary view in side elevation of another embodiment of the anti-torpedo shield of the invention; and,

Fig. 8 is an enlarged fragmentary view of the embodiment of Fig. 7 taken along the line 8—8 of Fig. 7.

In general, in accordance with this invention there is provided a dirigible, buoyant, longitudinally rigid shield of relatively narrow beam, but of a length and depth preferably not less than the length and draft, respectively, of the vessel to which it is designed to afford protection.

The embodied shield is suitably fashioned, proportioned and dimensioned so that when water-borne it will assume and tend to remain in a vertically upright substantially awash position at all times. Hence, when positioned in

suitably spaced relation to and on either side of a vessel, the shield will serve as a barrier against which a torpedo directed at the side of the vessel will strike, the shield being of sufficient strength as to explode, stop, deflect or foul the torpedo before it reaches the vessel.

The shield, as embodied, may be of wholly rigid construction or may have a flexible, semi-rigid, or other suitable form of lower structure providing a protective structure for the vessel's hull.

Rudder means are incorporated in the embodied shield structure for steering the shield in response to a steering effort transmitted thereto from the vessel.

Means are provided for towing the shield from and in suitably laterally spaced substantially parallel relation to the vessel and for automatically actuating the rudder means in response to a change in course of the vessel or shield so as to correct the course of the latter and speedily re-

establish the parallel course relationship of vessel and shield.

The embodied towing and rudder actuating means comprises a system of flexible spring-line cables which connect the vessel to the shield and to the rudder means of the latter.

The rudder actuating cables have the primary function of transmitting a steering effort to the rudder means and the additional function of transmitting a towing effort to the shield when the course of the shield has diverged far enough from the course of the ship, and vice versa.

The rudder actuating cables are suitably connected to the rudder so that as the vessel proceeds on a normal straight course, the shield will be caused to follow alongside the vessel in substantially parallel course relationship. However, upon a change in course of the vessel or shield, the distribution of load between the various cables of the system will become such as to actuate the rudder means in proper sense and magnitude and cause the shield to turn relative to or with the vessel so as to maintain or restore the parallel course relationship.

The various cables of the system are preferably releasably anchored to the ship so that they all may be quickly cast off from the vessel and will sink. Weights may be attached to the cables at their ends to facilitate their sinking so that the shield with its cables will not foul the ship.

It will be understood that the foregoing general description and the following detailed description as well are exemplary and explanatory but are not restrictive of the invention.

Referring now more particularly to the embodiment of the invention shown in Figs. 1 to 6 inclusive of the accompanying drawings, buoyant shield structures 10 are positioned on either side of and in spaced parallel relation to the keel of a towing vessel 11. They form a protective barrier therefor throughout the length and depth of the vessel.

Each of the shield structures 10 is connected to the vessel 11 by a cable system by which towing and steering of the shield structure is effected. It will be understood that each cable system performs the same function for its shield structure and the systems differ only in the manner in which they are rigged. A description of one shield structure and its cable system is therefore deemed to be sufficient to enable those skilled in the art to understand the construction of either, bearing in mind the minor obvious differences in cable rigging necessary for corresponding operation of the port and starboard shield structures.

Referring now more particularly to Figs. 3 to 6 inclusive, each shield structure 10 as here embodied, comprises a shield member 13 of laminated construction.

The shield member 13, as embodied, is preferably fashioned from material, such, for example, as wood which can be fabricated easily into a strong substantially rigid structure capable of impeding and preferably, stopping, deflecting, exploding or fouling a torpedo. As here embodied, it comprises a series of laminae 16 of wood or other suitable fibrous material, the several laminae being in cross-grained relation to each other.

The laminae 16, as here embodied, respectively comprise wood planks 17 of suitable width and thickness. A shield member of four inch thickness, for example, may be formed of four layers

of one inch by four inch planks in edge joined relationship.

In forming the shield member 13, the planks 17 may be coated with a cold setting, waterproof resin adhesive, preferably one which sets under a relatively low pressure. With such an adhesive, the laminae can be adhesively bonded to each other into a substantially unitary structure possessing superior strength and capable of being immersed in sea water for long periods of time without deterioration.

In assembling the laminae, the wood grain of the two inner layers runs diagonally of the shield member in opposite directions and the wood grain of the two outer layers run horizontally so as to obtain a cross-grained relationship. Nails 18, or other suitable fastening means, are preferably employed for joining the several layers to each other, during assembly, for providing the necessary pressure to set the adhesive and for holding the laminae together until the adhesive has set.

Means are provided for maintaining the shield structure 10 in an upright position when water borne. As here embodied, a keel member 14 of heavy metal is secured to the bottom of the shield member 13 with which it is coextensive. The mass of the member 14 is preferably sufficient to overcome the normal buoyancy, if any, of the shield member 13, per se, so that in the absence of any other buoyancy providing structure, the shield structure would sink.

Means are provided for buoying the shield structure 10 in the water so that in its normal water-borne position it will float vertically with its top substantially awash. The embodied buoyancy means may be in the form of a hollow spar secured to the top of the shield member 13 and coextensive therewith or may comprise a series of individual watertight buoyancy chambers secured to the sides of the shield member or may take such other form of hollow buoyancy device as will, when punctured and filled with water, cause the shield structure to sink. As here embodied, a pair of float members 19 and 20 are secured to the shield structure 10 at its top, one on either side of the shield member 13 so as to form therewith a pair of watertight buoyancy chambers 22 and 23. Bolts 21 are passed through suitable openings in the float members 19 and 20 and shield member 13 and serve to hold the float and shield members in firm watertight engagement.

The float members 19 and 20 as here embodied are of similar contour and of a length substantially coextensive with that of the shield member 13. Each is preferably contoured in any suitable fashion fore and aft so as to minimize resistance to movement through the water. As here embodied, each is fashioned of metal, preferably one having corrosion resistant properties, and is of sufficient thickness and strength to withstand rupture under the normal conditions of surface. It is apparent, however, that if the float sections be ruptured, as by a torpedo explosion, the buoyancy chambers 22 and 23 will fill with resulting loss of buoyancy so that the shield structure, if cast off from the towing vessel, will sink and not become a menace to navigation or give rise to the possibility of fouling the towing vessel's screws.

Means are provided on the shield structure for fending the shield structure as a whole away from its towing vessel when alongside. The embodied fending means may be of metal, cork or wood and may be round, streamlined or of any other

shape or material best suited for the purpose. As here embodied, fender members 24 are provided at suitably spaced points longitudinally and vertically of the shield structure. Each of the fender members 24 is preferably constituted by a section of hollow tubing bent to a generally streamlined shape and secured at either end to the shield structure as by bolts, screws or other suitable fastening means (not shown).

Rudder means are provided for steering the shield structure. As here embodied, a rudder 25 of a practically efficient area, is pivotally mounted at the stern of the shield structure upon posts 26 extending from the shield member 13. The rudder 25 is preferably coextensive in depth with the shield member 13 and is provided at its top with a rudder bar 27 which is connected to a tiller member 28 by a pair of cables 29 respectively connecting the corresponding ends of the rudder bar and tiller member.

The tiller member 28 is pivotally mounted and anchored midway of its end upon the shield member 13 by means of a pin and anchor structure 30. The structure 30 is of strong and rugged construction so as to absorb and transmit to the shield structure all of the forward pull exerted by the steering cables except for that which is necessary to turn the rudder.

Cable means are provided for towing the shield structure 10 and for actuating the rudder 25. As here embodied, a towing cable 31 and a pair of rudder actuating cables 32 and 33 connect the vessel 11 with each shield structure.

Means are provided for adjusting the cables 31, 32 and 33 separately as to length, for locking all of the cables to the vessel while under way and for quickly releasing the cables from the vessel so that the shield structure may be cast adrift if the need arise. The embodied adjusting, locking and releasing means preferably comprises one or more winches and as here embodied comprises a multiple winch unit 34 for winding and unwinding each of cables 31, 32 and 33 separately, for locking all three cables while underway and for releasing the cables quickly if the need arise.

The outboard end of the towing cable 31 is connected to the shield 10 preferably adjacent the top of the latter and preferably at a region forward of the longitudinal mid-point thereof. The cable 31, as here embodied, terminates at its outboard end in a bridle 35 of which the respective arms are anchored in any suitable fashion to the float section 19. Thus, it will be seen that the bridle 35 permits the shield 10 to be towed much in the fashion in which a kite is towed through the air. It will be understood, however, that the bridle 35 may be dispensed with, if desired, and the cable 31 directly connected to the shield 10.

The bow steering and towing cable 32 constitutes a running line which runs, as viewed in Fig. 1, forwardly around a bow sheave member 36, thence sternward longitudinally of the shield member 10 to a stern sheave member 37 and thence around the outboard side thereof to the inboard end of the tiller member 28.

The stern steering and towing cable 33 also constitutes a running line which, as viewed in Fig. 1, runs rearwardly of the vessel 11 around a sheave member 38 located astern of the point where towing cable 31 joins the shield, thence sternward longitudinally of the shield member 10 parallelly of the cable 32 to the sheave member 37 and thence around the inboard side 75

thereof to the outboard end of the tiller member 28.

The cables 31, 32 and 33 provide a system of spring lines between the vessel 11 and the shield 10 so that relative vertical and horizontal movement of vessel and shield structures may take place without imposing undue stress upon the towing and steering cables, or upon the shield structures, or vessel. Greater springing effect may be obtained by increasing the weight of the cables, or by employing heavier cables, or by providing weights (not shown) attached to the cables between the vessel and shield structure.

It will be observed that the shield structure 10 will be towed through the water by the vessel 11. With the vessel 11 on a straight course and the shield structures at their normal distance from the vessel on a corresponding course in which they generally parallel the vessel's keel, the main 15 towing effort is transmitted to the shield structures through the respective towing cables 31. Should either shield structure work in toward the ship from its normal running position set by the length of the cables, some of the towing effort 20 would be transmitted to the shield structure through its stern steering cable 33. Veering of the bow of a shield structure toward the ship 25 produces a similar effect.

If either the vessel or a shield structure change 30 course in relation to the other, one of the cables 32 and 33 will be slackened and the other tautened. In consequence, the rudder 25 will be moved so as to cause the shield structure 35 speedily to change course sufficiently to reestablish the original course relationship.

For example, assume a starboard turn of vessel 11, the cable 32 of the starboard shield will slacken and the stern cable 33 tauten. The cable 33 will exert a direct pull on the shield structure at sheave 38 tending to turn it to starboard. Cable 33 will also move tiller member 28 counterclockwise, as viewed in Fig. 1, the cable 32 having slackened. The rudder 25 is thereby correspondingly moved a sufficient amount to turn 45 the shield structure promptly into a course paralleling that of the vessel.

Assuming a port turn of the vessel, cable 32 of the starboard shield will tauten and cable 33 will slacken. Cable 32 will exert a direct pull on the shield structure at sheave 36 tending to turn the shield structure to port. The pull of cable 32 will turn rudder 25 clockwise and the shield structure will be caused to turn to port promptly 55 into a course paralleling that of the vessel. It is apparent that the port shield structure will be steered so as to obtain a corresponding result.

Should the shield structure deviate in course 60 relative to the vessel, it will automatically be restored to its initial desired course by the action of cables 32 and 33. Thus, the shield structure is self-steering.

Referring now to the embodiment of the invention shown in Figs. 7 and 8, the shield member 13 comprises an upper web or spar member 40 from which depend the bow and stern anchor frames 41 and 42.

The spar member 40 is preferably constructed of sheet steel and is of shallow depth relative 70 to its length. The anchor frames 41 and 42 are preferably formed of steel tubing bent into a roughly U-shaped structure which is welded or otherwise suitably anchored at the tube ends to the spar member 40. The front tube of each frame preferably extends downwardly and rear-

wardly while the rear tube extends vertically downwardly. By this arrangement a stiffer structure is obtained.

A net 43 of cable construction is suspended from the spar member 40, the latter being provided with a series of apertures 44 for the reception and anchoring of the various vertical lengths of cable of the net. Further anchoring of the net is effected at bow and stern by fastening the cables of the net to the anchor frames 41 and 42 which may be apertured to receive the various cable ends.

The bottom of the net 43 is also anchored to the anchor frames 41 and 42 and to a cable 45 secured at either end to the anchor frames 41 and 42. The cable 45 assists in maintaining the shield structure in an upright position when water-borne. It will be understood that the net 43 may or may not be taut. For example, it may be anchored against the drag of the water at the front only.

Buoyancy means comprising the float sections 46 and 47 are welded or otherwise suitably secured to the spar member 40 and form therewith buoyancy chambers 48 and 49 by which the shield structure is water-borne in a substantially awash and vertical position. As in the embodiment of Figs. 1-6, inclusive, rupture of the float sections and filling of the compartments 48 and 49 is destructive of the buoyancy so that the shield structure will sink.

Fenders 50 similar to the fenders 24 are secured to the spar member 40 at suitably spaced intervals and a rudder 51 is mounted on rudder posts 51' carried by the anchor frame 42.

The rudder 51 may be relatively short since the main rudder action will be with reference to the float structure comprised by the float sections 46-47 and the spar member 40, the balance of the shield structure offering little lateral resistance to the water.

A rudder bar 52 is connected to a tiller member 53 by connecting cables indicated by cable 54 in Fig. 7. It will be understood that the construction and operation of the rudder bar 52, tiller member 53 and the connecting cable thereof is substantially the same as the construction employed in the embodiment of Figs. 1-6 inclusive.

Towing and steering of the shield structure is accomplished by the cables 31, 32 and 33 just as has been described with reference to the embodiment of Fig. 1.

Thus, it will be seen, that in the embodiment of the invention depicted in Figs. 7 and 8 there is provided a shield structure which is buoyant, self-steering and possesses the desirable attributes previously referred. In addition it has somewhat less tendency to lateral drift by reason of the open work construction of its major portion of its under water structure.

The invention in its broader aspects is not limited to the specific mechanisms shown and described but departures may be made therefrom within the scope of the accompanying claims without departing from the principles of the invention and without sacrificing its chief advantages.

What I claim is:

1. An anti-torpedo shield to be used with a marine vessel comprising a buoyant dirigible shield structure having rudder means; and, means for connecting said shield structure to said vessel, said means comprising cables forming running lines with said shield structure for

actuating said rudder means in response to a change in course of said vessel or said shield structure and a separate cable for towing said shield structure from said vessel.

5 2. An anti-torpedo shield to be used with a marine vessel comprising a buoyant dirigible shield structure having rudder means; and, means for connecting said shield structure to said vessel, said means comprising cables forming running lines with said shield structure for actuating said rudder means in response to a change in course of said vessel or said shield structure and a separate cable for towing said shield structure from said vessel said towing cable being anchored to said shield structure forward of the longitudinal mid point of said shield structure.

10 3. An anti-torpedo shield to be used with a marine vessel comprising a buoyant dirigible shield structure having buoyancy compartments providing a negative buoyancy when filled with water and having rudder means; and, means for connecting said shield structure to said vessel, said means comprising cables forming running lines with said shield structure for actuating said rudder means in response to a change in course of said vessel or said shield structure and a separate cable for towing said shield structure from said vessel.

15 4. An anti-torpedo shield to be used with a marine vessel comprising a buoyant dirigible shield structure having rudder means; and, means for connecting said shield structure to said vessel, said means comprising cables forming running lines with said shield structure for actuating said rudder means in response to a change in course of said vessel or said shield structure and a separate cable for towing said shield structure from said vessel, said cables being adapted to form a spring-line system between said shield structure and said vessel.

20 5. An anti-torpedo shield to be used with a marine vessel comprising a buoyant dirigible shield structure having rudder means; and, means for connecting said shield structure to said vessel, said means comprising cables forming running lines with said shield structure for actuating said rudder means in response to a change in course of said vessel or said shield structure and a separate cable for towing said shield structure from said vessel said towing cable being anchored by a bridle member to said shield structure forward of the longitudinal mid point of said shield structure.

25 6. An anti-torpedo shield to be used with a marine vessel comprising a buoyant dirigible shield structure of laminated construction having rudder means; and, means for connecting said shield structure to said vessel, said means comprising cables forming running lines with said shield structure for actuating said rudder means in response to a change in course of said vessel or said shield structure and a separate cable for towing said shield structure from said vessel.

30 7. An anti-torpedo shield to be used with a marine vessel comprising a buoyant dirigible shield structure of net construction having rudder means; and, means for connecting said shield structure to said vessel, said means comprising cables forming running lines with said shield structure for actuating said rudder means in response to a change in course of said vessel or said shield structure and a separate cable for towing said shield structure from said vessel.

8. An anti-torpedo shield to be used with a marine vessel comprising a buoyant dirigible shield structure having rudder means; and, means for releasably connecting said shield structure to said vessel, said means comprising cables forming running lines with said shield structure for actuating said rudder means in response to a change in course of said vessel or said shield structure and a separate cable for towing said shield structure from said vessel.

9. An anti-torpedo shield to be used with a marine vessel comprising a buoyant dirigible shield structure having rudder means; and, means for connecting said shield structure to said vessel, said means comprising cables forming bow and stern running lines with said shield structure for actuating said rudder means in response to a change in course of said vessel or said shield structure, and a separate cable anchored to said shield structure intermediate the bow and stern cables for towing said shield structure from said vessel.

10. An anti-torpedo shield to be used with a marine vessel comprising a buoyant dirigible shield structure at least coextensive in length and depth with the length and draft respectively of the vessel with which it is to be used, said shield structure having rudder means; and, means for connecting said shield structure to said vessel, said means comprising cables forming running lines with said shield structure for actuating said rudder means in response to a change in course of said vessel or said shield structure and a separate cable for towing said shield structure from said vessel.

11. An anti-torpedo shield to be used with a marine vessel comprising a buoyant dirigible shield structure, said shield structure comprising a shield member, float sections secured to said shield member and forming watertight buoyancy chambers therewith, a plurality of fender members secured to said shield member, and rudder

means carried by said shield member; and, means for connecting said shield structure to said vessel, said means comprising cables forming running lines with said shield structure for actuating said rudder means in response to a change in course of said vessel or said shield structure and a separate cable for towing said shield structure from said vessel.

12. An anti-torpedo shield to be used with a marine vessel comprising a buoyant dirigible shield structure, said shield structure comprising a shield member of wood laminae adhesively bonded together into an integral structure, float sections secured to said shield member and forming watertight buoyancy chambers therewith, a plurality of fender members, and rudder means carried by said shield member; and, means for connecting said shield structure to said vessel, said means comprising cables forming running lines with said shield structure for actuating said rudder means in response to a change in course of said vessel or said shield structure and a separate cable for towing said shield structure from said vessel.

13. An anti-torpedo shield to be used with a marine vessel comprising a buoyant dirigible shield structure, said shield structure comprising a shield member of wood laminae adhesively bonded together into an integral structure by a synthetic resin adhesive, float sections secured to said shield member and forming watertight buoyancy chambers therewith, a plurality of fender members, and rudder means carried by said shield member; and, means for connecting said shield structure to said vessel, said means comprising cables forming running lines with said shield structure for actuating said rudder means in response to a change in course of said vessel or said shield structure and a separate cable for towing said shield structure from said vessel.

WADSWORTH W. MOUNT.
